UNITED STATES PATENT OFFICE.

JESSE E. LA DOW, OF JACKSON, MICHIGAN, ASSIGNOR OF ONE-HALF TO FORREST C. BADGLEY, OF JACKSON, MICHIGAN.

SIDE CURTAIN FOR VEHICLE-TOPS.

1,098,451.

Specification of Letters Patent. Patented June 2, 1914.

Application filed August 5, 1913. Serial No. 783,052.

To all whom it may concern:

Be it known that I, JESSE E. LA Dow, a citizen of the United States, residing at Jackson, Jackson county, Michigan, have invented certain new and useful Improvements in Side Curtains for Vehicle-Tops, of which the following is a specification.

This invention relates to improvements in side curtains for automobile tops, and for 10 side curtains for carriage tops in general.

The objects of this invention are to provide a simple and efficient means for storing the side curtains along the horizontal part of the top bows, and of quickly attaching 15 them inside the bows when it is desired to put the curtains in position.

A further object, is to provide improved tensioning means whereby the manipulation of the curtain is greatly facilitated.

20 Further objects relating to details and economies of construction and operation will definitely appear from the detailed description to follow.

I accomplish the objects of my invention 25 by the devices and means described in the following specification.

The invention is clearly defined and pointed out in the claims.

A structure which is a preferred embodiment 30 of my invention is fully illustrated in the accompanying drawing, forming a part of this specification, in which:

Figure I is a detail perspective view of the back bow of an automobile top with the 35 curtains stored according to my invention.

Fig. II is a vertical longitudinal central section through the rear portion of an automobile top showing the position of the rear section of curtain when it is in use.

40 Fig. III is a detail view of one of my improved curtains in position to be rolled up, showing its relation to the top and method of securing the same. Fig. IV is a detail view of one of the hooks for the tension 45 and attaching spring for securing the curtain and for putting tension on the same when it is being rolled up for storage.

In the drawing similar numerals of reference refer to similar parts throughout the 50 several views.

Considering the numerals of reference the top bow 1 is shown in Fig. I with the side curtains 3 rolled up upon the same the top bow being provided with the usual side 55 members 2. The curtain is the usual con-

struction of side curtain with gromets 4, 5 and 6 for securing it at the upper ends to the bows and back, and gromets 7, 8 and 9 for securing the lower ends of the curtain to the inside of the top. I provide a screw eye 60 10 for engagement through the gromet 4 at the upper edge of the curtain. I provide a tension spring 11 which is secured by a screw eye 12 to the upper central curved portion of the top bow. This is provided at its free 65 end with a hook which preferably has a loop for convenience in handling, although such loop is not essential.

When the curtain is in position the hook 13 is hooked through the eye 10 after the 70 curtain has been put into position and serves as an effective means for securing the upper edge of the curtain to the inside of the top bow. When it is desired to store the curtain this hook is withdrawn from the screw 75 eye 10 and is hooked into one of the gromets. A fastener 14 is provided at the central part of the bow and the edge of the curtain is secured thereto in any suitable way. The curtain on the opposite side is disposed across 80 the bow top and secured to the same fastener, and the two curtains are then rolled up into a close package together and retained in position by a pair of wire loops 15 engaging a suitable button or buckle as 85 shown. The spring, with the hook, effectively secures the upper edge of the curtain to the top and when the hook is engaged in the gromet, and the curtain secured to the central fastening it is held very evenly under tension in position and can be readily 90 rolled up and retained by the strap.

While I have shown coiled wire loops for holding up the curtains, which have marked advantages, any suitable fastening might be 95 used.

I desire to state that the structure as shown can be considerably varied without departing from my invention. I believe the specific structure to be valuable, and I desire to claim the specific structure as well as the broader features which appear in the appended claims.

Having thus described my invention, what I claim as new and desire to secure by Letters Patent is:

1. The combination of a bow for a top, a spring pivotally secured to the central part of the curved bow portion and provided with a hook at its free end, a curtain with suit- 110

- able eyes or gromets, the hook on said spring engaging one of the upper gromets, a fastener at the center of the bow to receive the edge of the curtain whereby the curtain is secured in position by the spring and is secured under tension that it may be wrapped up, and a loop secured to the bow for retaining the rolled-up curtain in place, all coacting substantially as described for the purpose specified.
2. The combination of a bow for a top, a spring pivotally secured to the central part of the curved bow portion and provided with a hook at its free end, a curtain with suitable eyes or gromets, the bow at the top to engage the eye on the upper gromets, a fastener at the center of the bow to receive the edge of the curtain whereby the curtain is secured in position by the spring and is secured under tension that it may be wrapped up, and a coiled wire loop secured to the bow for retaining the rolled-up curtain in place, all coacting substantially as described for the purpose specified.
3. In a side curtain structure for an automobile, the combination with a curtain, of a suitable spring for retaining the curtain in position while in use and for applying tension thereto when the same is rolled and

stored along the horizontal part of the top 30 bow, as specified.

4. In a top, the combination of a bow, a curtain provided with suitable fastening eyes or gromets, a spring secured to the curved portion of said bow and carrying a 35 hook at its free end, a screw eye on said bow in position to project through one of said gromets when the curtain is in closed position, a hook on the end of said spring being adapted to engage said screw eye to hold the 40 curtain in closed position, a fastener at the center of the bow to receive the edge of the curtain, the hook on the end of said spring being adapted to engage in one of said gromets whereby the curtain is secured under tension so that it may be rolled up, and a loop secured to the bow to retain the 45 rolled up curtain in place, all coacting substantially as described for the purpose specified.

In witness whereof, I have hereunto set my hand and seal in the presence of two witnesses.

JESSE E. LA DOW. [L. S.]
